UNITED STATES PATENT OFFICE

157,478

CHAIR

John Farkas, Jr., Chicago, Ill.

Application April 26, 1947, Serial No. 138,651

Term of patent 14 years

(Cl. D15—8)

To all whom it may concern:

Be it known that I, John Farkas, Jr., a citizen of the United States and a resident of Chicago, in the county of Cook and State of Illinois, have invented a new, original, and ornamental Design for Chair, of which the following is a specification, reference being had to the accompanying drawing, forming part thereof.

Fig. 1 is a top plan view of a chair showing my new design.

Fig. 2 is a front elevational view of Fig. 1.

Fig. 3 is a right-hand end elevation of Fig. 1.

The characteristic ornamental feature of my new design resides in the sloping seat member with respect to the base portion of the chair.

I claim:

The ornamental design for a chair, as shown and described.

JOHN FARKAS, JR.
